UNITED STATES PATENT OFFICE

2,150,643

ELECTROILLUMINATING ADVERTISING DEVICE

Arthur J. Waterman, New York, N. Y.

Application April 25, 1938, Serial No. 204,066

7 Claims. (Cl. 40—130)

The invention relates to an electro-illuminating advertising device particularly to be used for in-door advertising and display.

The object of the invention is the provision of a novel carrier which supports and encases all the accessories of the device particularly the illuminating tubes and the electrical equipment,

which further represents an attractive and effective reproduction of the article to be advertised and displayed,

which can be mass-produced in a simple and cheap manner,

which is provided in a process of manufacture with openings, channels and recesses for the reception of all its accessories,

which ensures a reliable and safe mounting of said accessories and

which is superior to known devices of this kind in point of manipulation, practical operation and use.

With advertising devices of the present type the utilization of a reproduction of the article to be advertised has already been suggested; such reproduction has e. g. been shown as casing of a radio-receiving set said set being provided with a cover supporting the transformer and the terminals of the illuminating tubes.

Advertising devices of this type have also been designed as a bottle, said bottle encasing a transformer and a tube which extends through the neck of the bottle and is bent to the shape of the desired advertisement.

The main drawback of these known devices is their unsufficient applicability to practical use.

The costs of production are far too great for mass-production. The mounting of the accessories particularly the illuminating tubes and the electrical outfit is complicated and unsafe; consequently there is the great danger of being easily damaged; this is a grave disadvantage in the present case because the important requirement of these devices is that they can be handled by the user without excess of precaution.

These drawbacks of the known devices are obviated by the invention.

With this purpose in view the present device represents a reproduction or dummy body of the article to be advertised made from a mouldable or plastic material, e. g. gypsum, artificial wood and stone compositions, artificial resins and the like the recesses and openings for the reception and the mounting of all accessories being provided during its manufacture by casting, moulding, pressing and similar methods; these recesses, openings and channels are provided in

conformity with the shape of the illuminating tubes and the equipment connected therewith and being necessary to operate the same and to fasten it onto the carrier. Therefore this carrier represents a ready-made supporting body for the illuminating tubes and the electrical equipment connected therewith. To mount the tubes and its accessories on the supporting article no additional means are needed. Thereby an exceedingly cheap production and a safe handling of the advertising sign is ensured.

The invention is illustrated in its present embodiment as a shoe display device, the supporting body for the illuminating sign therefor having the shape of a shoe body, which may be covered with leather, fabrics or other materials used in the shoe manufacture and show the characteristic outside features of a shoe. The illuminating sign consisting e. g. of neon glass tubes is located on and adjacent to the side face of the shoe body. The body has preferentially several times the size of a normal shoe. It is made from a mouldable material and all the recesses, channels and opening for the reception and the mounting of the illuminating tubes, its associated parts, the transformer and the connection with the latter are provided in the supporting body during its manufacture by the application of suitable cores.

The invention is illustrated by way of example in the annexed drawing of which

Fig. 1 shows a side view of one half of the displayed article and,

Fig. 2 shows a horizontal section on line A—B.

The article which has been selected to illustrate the invention by way of example consists of a shoe body 1 showing on its outside all the characteristic features of a man's half-shoe. It is made from mouldable material and may be covered with leather, rubber or any other material used in the shoe-manufacture, or fabrics, paints and the like. The body 1 being shown as on half of a shoe dummy and having a size which preferentially exceeds several times the size of a normal shoe is made from the mouldable material by any suitable method, this material preferably being reinforced by inserts, burlap, screening, metal and the like.

The illuminating sign constituted by the glass tubes 2 and forming the inscription "Bestmade" 50 is located in front of the body 1; the tubes 2 are mounted in and on this supporting body 1 by means of the return tube sections 7, 11, these return tube sections are inserted in the channels 9 and 4 leading from the recess 3 for the 55

transformer 5 to the front face of the carrier or supporting body 1.

A second illuminating tube system 12 is provided to follow the outline of the shoe body 1.

5 For the mounting of this second illuminating system the same arrangement is chosen. Accordingly two channels 13a, b are provided in the body 1, which lead from the front face to the transformer 5 and receive the return tube sections 14a and 14b of the second tube system 12.

The transformer is provided with a contact plug 15. The advantages of the invention are fully apparent from the foregoing description.

15 The carrier fully symbolizing on its outside and by its shape and its contours the article to be displayed represents a ready-made or finished mounting for the illuminating tubes, the transformer and the entire electrical operating equipment. It is provided during the manufacture there of with the recesses and channels 3, 4, 9, 13a and 13b from the transformer recess 3 to the front side.

20 The illuminating signs are as a whole inserted into these channels with their return tube sections 11, 7, 12 these sections producing at the same time the connection with the transformer and the support of the signs in the carrier 1. To further assure a solid and reliable support 25 of the tube holders 16a, 16b, may be inserted in holes 17a, 17b of the carrier 1, which are also provided in the carrier during its production. These holders preferentially consist of glass tube sections forming one structural unit with the illuminating tubes.

30 A contact plug 15 is provided to connect the transformer to a source of current.

35 The sign represents an easily transportable unit, which may be placed on floors, showcases, tables or may be hung up on walls and on the ceiling of display-rooms, show-windows and the like.

What I claim is:

40 1. An electro-illuminating and display device comprising illuminating tubes, a transformer, electrical operating equipment and a carrier for said tubes, said carrier representing the article to be displayed and consisting of mouldable material, recesses and channels within said carrier for mounting and introducing said illuminating tubes said transformer and said electrical equipment, said carrier being a ready-made mounting unit with avoidance of additional fastening means.

45 2. An electro-illuminating and display device comprising illuminating tubes, electrical operating equipment, a carrier for said tubes, said carrier representing a dummy body of the article to be displayed and consisting of mouldable material, said illuminating tubes being arranged on and adjacent to the outer face of said carrier, return tube sections, a transformer, a recess for said transformer, channels leading from the transformer-recess to the front face of said carrier for receiving said return tube sections in said carrier, a contact plug fastened to said transformer, said carrier thereby being a ready-

5 made mounting unit for said transformer said tubes and said electrical equipment with avoidance of additional fastening means.

3. An electro-illuminating advertising and display device comprising a carrier, a transformer, two illuminating tube systems, the one of said tube systems being located on and adjacent to the outer face of said carrier, the second of said tube systems following the outline of said carrier, return tube sections, said carrier forming 10 a dummy body of the article to be displayed and consisting of mouldable material, recesses and channels within said carrier for said transformer and said return tube sections, said carrier forming mounting means for the tubes within said 15 dummy body.

4. An electro-illuminating advertising and display device comprising illuminating tubes, a transformer, a body supporting said illuminating tubes, said supporting body representing a 20 dummy shoe and consisting of mouldable material, said shoe being provided with a recess to accommodate said transformer and with channels leading from said recess to the front face of said dummy shoe thereby forming a ready-made 25 mounting and supporting unit for said tubes, said transformer and accessory parts of said tubes with avoidance of additional fastening means.

5. An electro-illuminating advertising and display device comprising illuminating tubes, a transformer, a body supporting said illuminating tubes, said supporting body representing the article to be displayed and consisting of mouldable material, said body being provided with recesses 30 and channels for mounting and introducing said illuminating tubes said transformer and their operating accessories, holders for said tubes, recesses within said supporting body for introducing said holders thereby being a ready-made 35 mounting unit with avoidance of additional fastening means.

6. An electro-illuminating advertising and display device comprising illuminating tubes, a transformer, a supporting body representing the 40 article to be displayed and consisting of mouldable material, said body being provided with recesses and channels for mounting and introducing said tubes said transformer and their operating accessories, holders for said tubes, said 45 holders forming a structural unit with said tubes, and holes within said supporting body for fastening said holders.

7. An electro-illuminating advertising and display device comprising illuminating tubes, a 50 transformer, a body supporting said illuminating tubes, said supporting body representing at least half a dummy shoe having a complete front face and consisting of mouldable material, said shoe being provided with a recess to accommodate said transformer and with channels leading from said recess to the front face of said shoe thereby representing a ready-made mounting and supporting unit for said tubes, said transformer and accessory parts of said tubes with avoidance 55 of additional fastening means.

ARTHUR J. WATERMAN.
